Application July 13, 1936, Serial No. 90,324
Renewed June 17, 1940

8 Claims. (Cl. 68—253)

This invention relates to clothes wringer and particularly to mechanism for safety release, pressure adjustment, roll stop, and reset.

One object of the invention is to provide novel means for simply and quickly adjusting the roll pressure for selective (low, medium and high) roll pressure when the wringer is reset into operative position.

Another object is to provide a clutching mechanism cooperating with the safety release whereby the rolls are stopped from rotation responsive to the operation of the safety release and again started in rotation when the wringer is reset into the closed or operating position.

Other objects and improvements will be disclosed by reference to the following description and drawings, in which:

Fig. 1 is a front elevation of the complete wringer and head.

Fig. 2 is a sectional front elevation disclosing the interior relation and arrangement of the parts.

Fig. 3 is a vertical cross section of the head and companion parts of the wringer on a larger scale to better disclose the mechanism.

Fig. 4 is a plan sectional view of the wringer on the section lines 4—4 of Fig. 1.

Fig. 5 is a vertical sectional view on section lines 5—5 of Fig. 4.

Fig. 6 is a sectional elevation view of the wringer drive gear and coupling on the large scale of Fig. 3 and taken in a plane represented by line 6—6 in Fig. 3 of the drawings.

Fig. 7 is a plan view of the boss on the upper frame on the line 7—7 of Fig. 1 but on the larger scale of Fig. 3.

Fig. 8 is a vertical section of the pressure adjustable mechanism on the line 8—8 of Fig. 1.

Referring to Fig. 1 it will be noted that the wringer and head are designed as a unit rather than as two units, wringer and head.

The general structure of the wringer and head includes a lower frame 40, and a top frame 10, normally mounted in slightly spaced relation, as shown at 10a in full lines in Fig. 1 and dotted lines in Figs. 2 and 3. The lower frame 40 extends laterally from and is carried by a gear head 46, by the intermedium of a gear head extension 46a. A pair of coacting rolls 41—42 are arranged respectively in the lower frame 40 and the top frame 10, being rotatably mounted in supporting bearings 41' and 42', respectively, and urged into pressure engagement with each other by a conventional leaf spring 32, as shown in Fig. 2. The lower roll 41 is driven by conventional reverse

gearing 43—44—45 mounted in the gear head 46, from a drive shaft 24. The connection of said drive shaft with the gearing 43—45 is through a slidable clutch element 48 mounted on the shaft 24, being splined thereto, and shiftable into clutch engagement with the respective gears 44 and 45 by means of a handle 47 mounted in a side of the gear head 46. The lower roll 41 is driven by the gear 43 by way of any suitable coupling means 43a.

10 The top frame 10 is supported on the lower frame 40 by means of upstanding extensions 40a and 40b of said lower frame, as shown in Fig. 2. The extension 40a has a notch 12 therein at the left in Fig. 2 in position to receive a cross rivet 13, fixed to the outer end of the top frame 10 to form a pivotal connection between said outer end of the top frame 10 and the extension 40a of the lower frame 40.

15 The inner end of the top frame 10 (at the right in Fig. 2) is supported for swinging and bodily movement relative to the extension 40b, by a pair of links 15—15' (Fig. 3). The links 15—15' are pivotally connected with the top frame 10 by a cross rivet 16, at one end of said links, while the opposite ends thereof are pivotally connected by studs 14, 14', with the extension 40b of the lower frame. The cross rivet 16 also pivotally supports on the top frame 10 a reset cap lever 11, as shown in Fig. 3. The cap lever 11 also rigidly carries lugs 11a connected by pivot 49 with a pair of links 17, 17', which in turn are pivotally connected at one end on the cross rivet 16', which is carried by the extensions 40b.

20 25 30 35 A bell-crank latch lever 18 pivotally mounted on rivet 19 is latchable on a cross bar 20 fixed to the gear housing and is tensioned towards latching position by torsion spring 21. The inside end of bell latch lever bears against safety release cap 22 holding it upward thru a slot in the reset cap. The inner end of the top frame 10 is held normally in locked position by the engagement of the latch lever 18 with the cross bar 20.

40 45 50 A bracket 23 is fixed to inside of reset cap 11 and positioned to hold the vertical wringer drive spline shaft 24 in its low or operating position whereby the upper clutch member 25 engages the lower or driven clutch member 26. The compression spring 27 bears against the ends of the driver and driven shafts 24', 24, respectively, and is arranged to separate the clutch members as shown in the dotted outline in Fig. 3 when the reset cap is released; also shown in dotted outline. The driven clutch member 25 is slidably and flexibly mounted on the shaft 24 by a pin and elongated

hole and tensioned downward by compression spring 28 in order to prevent a mismatching of the clutches such as would prevent the wringer from closing by permitting the driven clutch 28 to rise until matching occurs.

The pressure adjusting cap 30 is mounted on the upper frame 10 and carries a stamping 31 provided with a series or sets of steps or notches arranged to bear on spring 22 to give three variations of roll pressure corresponding to the low, medium and high or other markings on the adjusting cap.

With this general description of the parts, their functions will be understood by the following description of the operation of the wringer.

Assuming the wringer closed and in operation, by pressing downward on the safety cap 22, the bell latch lever 18 is disengaged from shaft 20 allowing the upper frame to move upward under spring pressure but constrained to a particular movement by the links 15-15' and 17-17' whereby the inner end of the upper frame first moves upward and then outward whereby the outer end of the upper frame is released by the disengagement of shaft 18 from notch 12.

During this movement the bracket 23 has moved away from contact with the upper end of the shaft 24 and the clutch members 25 and 26 have been separated by the action of spring 27, thus stopping the rotation of the wringer rolls.

Now the wringer can be easily reset by engaging the end bolt 13 in notch 12 and depressing the reset cap 11 into closed position. The powerful toggle lever action of the link mechanism greatly facilitates this operation.

Having thus described my invention, I now claim as new:

1. In a wringer of the class described, the combination of a relatively stationary wringer frame, a pair of co-operative rolls mounted in said stationary frame, a head mounted on said frame, roll driving gears mounted in said head, an upper frame pivotally connected to said stationary frame in a manner whereby said stationary and upper frames may be disconnected by longitudinal movement of the upper frame, links connecting one end of the upper frame to the stationary frame, a re-set cap also connected to the stationary frame and to said upper frame by pivoted links, a latch member on said head, a latch mechanism carried by said re-set cap and cooperative with said latch member for locking the upper frame to said head and stationary frame, a safety button carried by the re-set cap and cooperative with said latch mechanism for releasing the same, and mechanism in the wringer head cooperating with the re-set cap upon movement of the cap whereby to control the rotation of the wringer rolls.

2. In a clothes wringer having a head, a driving mechanism therein, a relatively stationary frame, wringer rolls mounted in said frame, an upper frame carrying means normally pressing said rolls into engagement with one another, links pivotally connecting said upper frame and stationary frame, a re-set cap pivotally associated with said upper frame, links pivotally connecting said re-set cap with said stationary frame, a lock mechanism between said cap and said head, a bar and notch connection between said upper frame at one end and said stationary frame at a place spaced from the last said pivotal connection, means associated with said re-set cap for releasing said lock mechanism, and mecha-

nism carried by said re-set cap for disconnecting said drive means when said lock mechanism is open and for connecting said drive means when said lock is closed.

3. In a wringer of the class described, a roll carrying frame including a roll driving gear supporting head and a pressure spring, roll driving gearing in said head, a roll-pressure spring compressing cap mounted on said frame and movable relatively thereto, a reset lever operatively connected with said frame and with said cap, cooperating latch devices carried by said lever and said head for retaining said cap and lever in roller-spring compressing position, a manually operable device for effecting disengagement of said latch devices from each other, clutch mechanism in said head, and means carried by the reset lever for effecting actuation of said clutch mechanism, responsively to movements of said lever.

4. In a wringer of the class described, a roll carrying frame including a roll driving gear supporting head and a pressure spring, roll driving gearing in said head, a roll pressure spring compressing cap mounted on said frame and movable relatively thereto, a reset lever operatively connected with said frame and with said cap, cooperating latch devices carried by said lever and said head for retaining said cap and lever in roller-spring compressing position, a manually operable device for effecting disengagement of said latch devices from each other, clutch mechanism associated with driving gearing for throwing the same into and out of driving relation to said rolls, and means on said lever for effecting actuation of said clutch mechanism to cause said gearing to drive said rolls when said latch devices are inter-engaged.

5. In a wringer of the class described, a roll carrying frame including a roll driving gear supporting head and a pressure spring, roll driving gearing in said head, a roll pressure spring compressing cap mounted on said frame and movable relatively thereto, a reset lever operatively connected with said frame and with said cap, cooperating latch devices carried by said lever and said head for retaining said cap and lever in roller-spring compressing position, a manually operable device for effecting disengagement of said latch devices from each other, spring means operatively associated with said driving gear for normally maintaining the same inactive to drive said rolls, and means on said lever operating counter to said spring means for maintaining driving relation of said gearing relatively to said rolls when said latch devices are inter-engaged.

6. In a wringer and gear head adapted to be mounted on a domestic washing machine, a supporting frame, rolls with pressure means mounted in the frame, pressure release and reset mechanism including pressure adjustment means mounted on the frame, roll driving means mounted in the head, said driving means including a vertically slid able shaft, a clutch mounted on said shaft, and means co-acting with the shaft and pressure release and reset mechanism to slide the shaft and actuate the clutch to engage the driving means when roll pressure is reset and to release the driving means when roll pressure is released.

7. In a wringer and gear head adapted to be mounted on a domestic washing machine, a supporting frame, rolls with pressure means mounted in the frame, pressure release and reset mechanism including pressure adjustment means

mounted on the frame, roll driving means mounted in the head, said driving means including a vertically slideable shaft, a spring retained clutch member slidably mounted on the shaft, and means co-acting with the shaft and pressure release and reset mechanism to slide the shaft and actuate the clutch to engage the driving means when roll pressure is reset and to release the driving means when roll pressure is released.

8. In a wringer and reversible gear head adapted to be mounted on a domestic washing machine, a supporting frame, rolls with pressure

means mounted in the frame, pressure release and reset mechanism including pressure adjustment means mounted on the frame, roll driving and roll rotation control mechanism mounted in the head, said driving mechanism including a shiftable splined drive shaft, a clutch slidably mounted on said shaft, and means co-acting with the shaft, pressure release and reset mechanism, and the clutch to control the clutch and the roll drive.

NICHOLAS L. ETTEN.
